H. A. CUMFER,
CONDUIT SYSTEM FOR VISCOUS MASTIC MATERIALS.
APPLICATION FILED OCT. 20, 1916.

UNITED STATES PATENT OFFICE.

HARRY A. CUMFER, OF CHICAGO, ILLINOIS, ASSIGNOR TO GUYTON & CUMFER MANUFACTURING COMPANY, OF CHICAGO, ILLINOIS, A CORPORATION OF ILLINOIS.

CONDUIT SYSTEM FOR VISCOS MASTIC MATERIALS.

1,247,937.

Specification of Letters Patent. Patented Nov. 27, 1917.

Application filed October 20, 1916. Serial No. 126,690.

To all whom it may concern:

Be it known that I, HARRY A. CUMFER, a citizen of the United States, residing at Chicago, in the county of Cook and State of 5 Illinois, have invented certain new and useful Improvements in Conduit Systems for Viscous Mastic Materials, of which the following is a specification.

My invention relates to improvements in 10 conduit systems.

One of the general objects of my invention is to provide a method of and a conduit system to conduct a normally viscous, slow-flowing fluid, such as asphalt, pitch, tar, or 15 like materials, or compounds thereof, which are substantially immobile at atmospheric temperature and which require application of heat to render them sufficiently fluid to be transmitted through relatively small 20 pipes.

A more specific object of my invention is to provide a system of pipe-connecting fittings and valves for conducting the heated medium, surrounded by an overlying jacket 25 providing an intervening space—for conducting the heating medium, such as steam, hot water or the like,—continuous through the fittings, valves, etc., over and around the interior conducting pipe sections and around 30 the pump that provides the power to urge the liquid through the conduit system.

Other and further objects of my invention will become readily apparent, to persons skilled in the art, from a consideration of 35 the following description when taken in conjunction with the drawings, wherein:

Figure 1 shows a pump, a receiver, and a schematic arrangement of my conduit sections and fittings, parts being broken away 40 to show other parts in section.

Fig. 2 is a transverse section taken on line 2—2 of Fig. 1.

In all the views the same reference characters are employed to indicate similar parts.

45 In the manufacture of composition shingles, and other similar roofing material, in which sheets of suitable fabric, such as felt, are coated or saturated with an asphaltic water or weather-resistant, such as asphalt, 50 pitch, tar or compounds thereof, the material or materials are heated in tanks and maintained at a suitable temperature to render them more or less fluid, and while in this state or condition the fabric is passed

through the body of fluid mastic substance, 55 thereby saturating or coating the more or less porous fabric base, to render it weather-proof.

This waterproofing material quickly chills and unless kept at a relatively high temperature, it becomes inexpedient to supply sufficient power to urge it through the conduit pipes and therefore a heating medium at a sufficiently high temperature is necessary to be supplied along the entire line of flow or 65 path of the medium to be heated.

In large manufactories, of this character, where more than one tank or asphalt container is used, it frequently becomes necessary, or desirable, to convey the water-proofing material from one tank to another, or from a central source of supply to any one of a plurality of tanks associated with respective fabric-moving and coating machines.

75 The problem of transferring and distributing the normally stiff asphaltic plastic from place to place is fraught with many difficulties. It chills too quickly to be successfully conducted through ordinary pipes 80 and fittings. It cannot be practically accomplished unless it be maintained at a temperature at which it will freely flow, otherwise it will clog the pipes, valves and other fittings through which it is caused to 85 pass.

To force the asphaltic material through a relatively small pipe requires it to be heated to and maintained at a temperature of about 300 degrees Fahrenheit. This temperature 90 is attained in the heating medium, such as steam, or water, by confining and subjecting it to a pressure between 50 and 60 pounds per square inch.

In the embodiment which I have chosen 95 to exemplify my invention, 5 is a jacketed pump driven by a belt that may be applied to a pulley 6. The pump is employed for the purpose of forcing the material through the conduit pipes. 7 is an inlet pipe or nipple which is preferably connected to a nearby tank, not shown, containing hot mastic to be transferred by the conduit system, as to a tank 8, or distributed to other suitable receptacles through branch pipes.

100 The conduit pipe system consists of an internal pipe 9 through which to convey the heated mastic material and an external

jacket pipe 10, between which and the pipe 9, a space is provided wherein to convey the heating medium or fluid, such as steam or water under pressure.

5 Owing to the inequalities of expansion and contraction of the parallel pipes I provide expansion joints 11, preferably for the outer pipes, to compensate for the differences in length, due to the differences in coefficient 10 of expansion or of temperatures to which they are heated.

The expansion joints, of which there may be any desired number in the system, and of which five are shown in the drawings, consist of a packing box 12 for the packing 13, that surrounds the pipe 10 and is compacted and held in place by the surrounding gland 14 that is freely slideable on the outer pipe.

The box 12 is preferably an integral part 20 of the larger flange-box 15, within which to contain the flange coupling 16 of the smaller inner pipe 9. The box 15 is provided with a coupling flange 17 for connection with a similar flange 18 secured to an

25 adjoining section of the pipe 10, as by bolts 19. The one end of pipe 10 enters the packing box 12 and is freely slideable therein to compensate for the relatively changing length of the parallel pipes, being made 30 steam-tight by the packing 13 and the bolts or studs 20-20, which pass through the flange 14' of the gland 14 and into the flange 12' of the box 12. Sufficient space 21, is left between the pipes 9 and 10, through 35 which the steam or water, under pressure or other heating medium, is designed to pass.

The fittings, consisting of the elbows 22, the T's 23, and the valve casings 24 are each 40 dual in character. Each of these exterior fittings is provided with an interior spaced apart similar fitting 22', 23' and 24', respectively. The inner fitting, in each case, is held in spaced relation from the outer fitting by suitably disposed chaplets 25. 45 The inner pipes 9 are secured to the inner-contained fittings without intermediary expansion joints. The outer pipes 10 are secured to the outer fittings by screw threads or by flanged couplings.

50 The steam or water space 21, between the inner and outer pipes 9 and 10, is continued by the space 26, between the inner and outer fittings and thus the space for the heating medium is made continuous throughout the 55 entire length of the conduit to permit a continuous flow of the heating medium, in

a path parallel with the flow of the medium to be heated.

A pipe 27 communicates with a space in the jacketed pump 5 and a pipe 28 communicates with the space 26 for the heating medium, in a remote end of the system. Either of these pipes may be used for the introduction of the heating medium and the other for the drain or discharge of the same, 60 at the remote end of the conduit system. The valves 29 control the flow of the heating medium. The valve 30 is operated by the hand wheel 31, and controls the flow of the heated medium through the pipes 9 into 70 the branches 32 and 33 of the system.

I prefer to use steam or water under 50 to 60 pounds pressure per square inch, which can be heated to 300 degrees Fahrenheit, or thereabout, in the interior steam space, 75 whereby to maintain the heated medium at approximately 300 degrees Fahrenheit, or more, throughout the path of its travel.

Having described my invention, what I claim is:—

1. A fitting for two concentrically-arranged pipe lines, comprising a box for housing the flange coupling of contiguous ends of pipes of the inner line; a flange disk for connection to the terminal of a pipe of the outer line overlying the outer end of said flange box; a packing box, for overlying an adjacent end of an outer pipe section, at the other end of the flange box; a gland, having a part to enter the packing box and overlying said end of the outer pipe, and means to draw the gland into said packing box into contact with packing to be contained therein.

2. In a system of the character described for conducting a viscous material comprising an inner line of pipes through which the material is to flow; a pump connected with said line of pipe; a steam jacket surrounding the pump; an outer line of pipe surrounding said inner line; a steam connection in the outer wall of the pump and expansion joints in the outer line of pipe to compensate for the difference in expansion of the two lines of pipe.

In testimony whereof I hereunto set my hand in the presence of two subscribing witnesses.

HARRY A. CUMFER.
